UNITED STATES PATENT OFFICE.

PAUL MAUSER, OF OBERNDORF-ON-THE-NECKAR, GERMANY.

MAGAZINE FOR SMALL-ARMS.

No. 808,938.

Specification of Letters Patent.

Patented Jan. 2, 1906.

Application filed July 22, 1903. Serial No. 186,543.

To all whom it may concern:

Be it known that I, PAUL MAUSER, a subject of the King of Würtemberg, and a resident of Oberndorf-on-the-Neckar, in the 5 Kingdom of Würtemberg, German Empire, have invented certain new and useful Improvements in or Connected with Magazines for Small-Arms, of which the following is a full, clear, and exact description.

10 The invention relates to a magazine for small firearms, particularly for automatic firearms, which is adapted for the reception of an exceptionally-large number of cartridges for the purpose of enabling patrols, outposts, 15 pickets, and other exposed troops to keep up a quick fire without stoppages for recharging. In magazines of this type the difficulty has always been to obtain a regular and uniform action or guiding of the cartridge carrier or 20 feeder which lifts the cartridges into the breech of the firearm and also to find suitable places for the necessary springs, inasmuch as owing to the great number of cartridges carried by the magazine springs of great length 25 and strength are evidently necessary, the perfect working of the same being dependent upon the guiding of the cartridge - feeder, which guiding should be effected as smoothly as possible and free from jamming and friction, 30 while the spring should be fixed in as simple a manner and occupy as little space as possible. Particularly when coiled springs are employed for magazines of this type the very long springs which become necessary 35 constitute a great obstacle if the space available be taken into consideration. In the arrangement of springs hitherto adopted an empty space in the magazine is necessary co-extensive with the springs when compressed, 40 which empty space is almost of the same length as that occupied by the springs when expanded if we assume that normally coiled springs are employed—that is to say, the waste space is nearly equal to the space in 45 the magazine available for cartridges. The magazine, therefore, has always had to be constructed nearly twice as long as is necessary for the reception of the cartridges; but apart from these obstacles there is one essential 50 condition which the employment of such attachable magazines demands, whether flat springs or coiled springs are used to lift the cartridges, which is to provide a device which will prevent the falling of the cartridges 55 from the magazine when the latter is detached and carried by the rifleman, which

device at the same time must allow of the immediate use of the magazine when it is again attached to the firearm without requiring further manipulation—that is to say, it 60 must allow the automatic successive release of the cartridges feeding the firearm.

Now the object of the present invention is to provide a magazine for small firearms which will fulfil the above conditions and at 65 the same time store a large number of cartridges, said magazine being attachable to the middle part of the stock of the firearm.

In the accompanying drawings, Figure 1 is a vertical section taken on the line 1 1 of 70 Fig. 2 of a magazine constructed according to the present invention, the device being shown attached to the stock of a firearm and its coiled springs working in parallel directions. Fig. 2 is a vertical cross-section thereof, taken on the line 2 2 of Fig. 1. Fig. 3 is a horizontal section thereof, taken on the line 3 3 of Fig. 1. Fig. 4 is a detail view of part of Fig. 1, illustrating more particularly the guiding means for the cartridge-feeder. Fig. 5 is a vertical transverse section taken on the line 4 4 of Fig. 4. Fig. 6 is a horizontal section taken on the line 5 5 of Fig. 4, the feeder, however, being shown in full lines. Fig. 7 is a side elevation of part of the magazine, 80 showing the arrangement of the lateral spring-lips. Fig. 8 is a vertical transverse section taken on the line 6 6 of Fig. 7. Fig. 9 is a similar view to Fig. 8, but showing the parts in different positions. Fig 10 is a side 85 elevation, partly in section, of a modified form of magazine. Fig. 11 is a horizontal section taken on the line 7 7 of Fig. 10, the feeder being shown in full lines. Fig. 12 is a similar view to Fig. 10, illustrating a further 90 modification; and Fig. 13 is a plan or top view thereof, partly in section.

In the several figures like parts are indicated by similar letters of reference, and Figs. 4 to 6 are drawn to an increased scale with respect 100 to the other figures of the drawings.

Referring to Figs. 1 to 9, M represents the magazine, which is constructed to hold about thirty cartridges and is provided with two coiled springs $f' f''$, which engage the feeder z 105 at the same end thereof and work in one and the same direction. The springs $f' f''$ are preferably arranged on both sides of the cartridge chamber or space m for the cartridges in special guide channels or recesses $g' g''$, formed in the magazine - casing M, which guide-recesses are separated by an in-

termediate wall g . At the bottom of the magazine - casing M a semicircular or **U**-shaped extension n is provided, and this extension n is formed with guide-recesses g^1 * 5 g^2 * around its periphery in continuation of the guide-recesses g^1 g^2 and similar thereto, thus allowing the springs f^1 f^2 to lie along both sides or ends of the magazine and around the semicircular bottom part or extension n —that is to say, to assume the shape of the letter **U**—and rest around the interior of the magazine. The cartridge carrier or feeder z is hinged by its rear extremity, which passes through a slot in the walls of the guide-recesses g^1 g^2 to a slide s capable of vertical movement within said recesses. This slide s is provided with rollers or runners r for the purpose of reducing friction, the prolonged axle o of which serves also as pintles for the feeder z . The top of the slide s is formed with a shoulder or tooth t , which obstructs the advance of the breech-bolt when the magazine is empty and the feeder z accordingly assumes its highest position. At its lower part the feeder has a recess v , in which a spring u is placed, one end of which abuts against the slide s and the other end of which takes a bearing against the end of the recess v with the tendency to adjust the feeder z into a slightly oblique position corresponding with the dimension or shape of the cartridges when the magazine is filled with the same. A spring-lip l is provided on the exterior of each of the side walls of the magazine, near to its top edge, which lips project across the mouth of the magazine when the latter is detached from the rifle, thus preventing the cartridges from dropping out, while said lips are rendered capable of being automatically released when the magazine is attached to the rifle by means of additional projections or the like, such as c , (shown in Fig. 9,) which may be arranged within the frame of the rifle. For this purpose the lips l , which are guided by suitable slots engaging headed studs or screws i , are provided with shoulders or projections k , which serve also as abutments for the bowed springs h , which are fastened to the studs or screws i , as shown at Fig. 7. The lips l must be connected with the screws i in such manner as to leave sufficient play between the parts to allow of a simultaneous elastic vertical and horizontal or outward motion of the same, as shown in Fig. 8, as regards the left-hand lip. The lower position of the lip is shown in full lines in Fig. 9 and in dotted lines in Fig. 7. In order to provide for the compulsory automatic retraction of the lips as above mentioned when the magazine is being attached to the rifle, the projections c in the frame are arranged to coact with the shoulders k in such manner that the latter are pressed downward when they come into contact with the former, and consequently the lips are re-

tracted. The magazine is maintained in position—as shown, for example in Figs. 1 and 3—by a spring-catch b , arranged within the trigger-guard, which device engages underneath the nose or projection d of the magazine and can be released by a pivotal lever or arm e , which engages a notch or recess b' in the catch b and has its pivot also within the trigger-guard a .

In the example given at Figs. 10 and 11 a modification of the arrangement above described is shown. In this case both the coiled springs f^1 f^2 , operating the cartridge-feeder z , are, as above described, situated in the guide-channels or recesses g^1 g^2 and the semicircular extension r ; but in this example they work in directions opposite to one another, the arm f^1 engaging the feeder at its rear end and the other, f^2 , operating upon its front extremity. The rear extremity z' of the feeder z is hinged to a sliding block s' capable of vertical movement within the guide channel or recess g^1 , while the front extremity z^2 of the feeder loosely engages another sliding block s^2 , which is capable of vertical movement within the recess g^2 . By this arrangement the correct working of the cartridge-feeder and the adjustment of the same in an oblique position (which in the example described with reference to Figs. 1 to 9 is afforded by means of a separate spring u) corresponding to that of the cartridges is now accomplished by the springs controlling the feeder themselves.

It will be understood that in some cases also a single spring of elliptical shape may be employed in the place of the two separate coiled springs of circular shape.

In the example given at Figs. 12 and 13 a guard K is provided at the top of the magazine, embracing the same at its rear part, and the cartridge-feeder is actuated by means of the well-known folding or laminated plate-spring f . In this case the lateral arms k^2 of said guard K carry the spring-lips l' , projecting into the mouth of the magazine. The guard K itself is maintained in position by a spring v' impinging upon its end part, and the arms k^2 are formed with downward extensions k^3 , which are provided with stamped projections k' for the purpose of enabling the guard K to be depressed and the lips l' to be retracted after the magazine has been attached to the rifle through the common engagement of the projections k' with corresponding projections in the frame.

What I claim as my invention, and desire to secure by Letters Patent, is—

1. In a magazine for firearms, a chamber for cartridges, and a spring for feeding the cartridges therein, extended in part around the exterior of said cartridge-chamber.

2. A magazine for firearms having a cartridge-chamber providing a substantially straight path for the cartridges, and a spring

for feeding said cartridges extending in part around the lower portion of said chamber.

3. A magazine for firearms having a cartridge-chamber, and a spring for feeding the cartridges therein, said spring extending in part along an end of said chamber and exterior to the same, beyond the path of movement of the cartridges, and being curved at the lower part of said chamber.

10 4. A magazine for firearms having a chamber adapted to contain cartridges, and a spring for feeding said cartridges, arranged at the exterior of said chamber and extended around the lower part of said chamber and 15 on both sides thereof.

15 5. A magazine for firearms, having a cartridge - chamber providing a substantially straight path for the cartridges, a guide extending at front and at rear of said path and 20 around the bottom thereof, and a spring in said guide adapted to feed said cartridges toward the top of said chamber.

25 6. In a magazine for firearms, a casing, a feeder in said casing, a guide extending around the lower end of said casing, and on both sides thereof, and a spiral spring in said guide for moving said feeder.

30 7. A magazine for firearms, comprising a substantially flat casing having a cartridge-chamber extending from bottom to top thereof, a guide extending along the front and rear ends of said casing, and around the bottom thereof, a feeder for said cartridges adapted to move in said chamber, a spring 35 having one end bearing against one end of said guide, and its other end bearing against said feeder to move the latter.

40 8. In a magazine for firearms, a casing, a feeder in said casing, a guide extending around the lower end of said casing in a semi-circular direction, and on both sides of said casing, said guide on one side having a slot opening into the interior of said casing, a slide adapted to move in said guide, and connected to said feeder through said slot, and a spiral spring one end of which engages said slide, and the other end of which bears against a fixed part on the other side of said guide.

45 9. In a magazine for firearms, a casing, a slide, a spring for moving said slide, a feeder pivoted at its end to said slide, and means for preventing said feeder from swinging downwardly around its pivot.

50 10. In a magazine for firearms, a casing, a slide, a spring for moving said slide, a feeder pivoted to said slide, and means for yieldingly holding said feeder in an oblique position in said casing.

55 11. In a magazine for firearms, a casing, a slide, a spring for moving said slide, a feeder pivoted to said slide, and means for yieldingly holding said feeder in an oblique position in said casing comprising a spring *u* acting against said slide.

60 65 12. In a magazine for firearms, a casing

having a guide, a slide having rollers moving along said guide, a spring for moving said slide, and a feeder pivoted to said slide.

13. A magazine adapted to be attached to and detached from a firearm, said magazine having an opening in its upper part, through which the cartridges are fed to the breech of said firearm, a sliding lip adapted to extend over said opening to retain the cartridges in said magazine when the latter is detached from the firearm, means adapted to engage a portion of the firearm to move said lip out of such position when the magazine is attached to the firearm, and a separate spring for automatically returning said lip to its operative position when the magazine is detached from the firearm.

14. A magazine adapted to be attached to and detached from a firearm, said magazine having an opening in its upper part, through which the cartridges are fed to the breech of said firearm, a sliding lip adapted to extend over said opening to retain the cartridges in said magazine when the latter is detached from the firearm, said lip having means for engaging a portion of the firearm whereby the lip is moved out of position when the magazine is attached to the firearm, and a separate spring adapted to move said lip upwardly into its operative position when the magazine is detached.

15. A magazine adapted to be attached to and detached from a firearm, said magazine having an opening in its upper part, through which the cartridges are fed to the breech of said firearm, two sliding lips normally extending over said opening from opposite sides of the magazine, and separate springs for moving said lips upwardly to their operative positions when the magazine is detached.

105 16. A magazine adapted to be attached to and detached from a firearm, said magazine having an opening in its upper part, through which the cartridges are fed to the breech of said firearm, loosely - mounted sliding lips, and separate springs for yieldingly holding said lips over said opening, in combination with a firearm having projections adapted to engage said lips to move the same out of the path of the cartridges when the magazine is attached thereto.

110 17. A magazine adapted to be attached to and detached from a firearm, said magazine having an opening in its upper part, through which the cartridges are fed to the breech of said firearm, two lips *l* adapted to slide longitudinally of the magazine, and springs *h* yieldingly holding said lips over said opening.

115 In witness whereof I have hereunto signed my name in the presence of two subscribing witnesses.

PAUL MAUSER.
